BOBBIN SUPPORTING APPARATUS

Pierre Charles Eppendahl, Lyon, France, assignor of one-half to Thermiguides S.A., Lyon, France, a company of France

Filed Feb. 16, 1965, Ser. No. 433,138
Claims priority, application France Feb. 18, 1964,

3 Claims. (Cl. 242—18)

This invention relates to apparatus for supporting bobbins in textile machinery and is more particularly concerned with apparatus for effecting the engagement and disengagement of the bobbins and their associated driving mechanism.

In such apparatus the bobbin on which yarn is to be wound is normally supported in a horizontal plane by a pair of arms holding it at each end, the arms being arranged to pivot as a unit about a parallel horizontal axis so that the bobbin can be brought into and out of engagement with a driving cylinder. The bobbin is at present normally held in engagement with the driving cylinder by gravity and is retained out of engagement by locking mechanism releasable upon actuation of a lever or handle.

Apparatus according to the present invention for supporting a bobbin in textile machinery comprises a bobbin support arranged to support a bobbin rotatably thereon and a pivotal connection between said bobbin support and a supporting structure permitting the support to pivot about an axis parallel to and displaced from the axis of rotation of the bobbin carried by the support so as to be movable from an engaged position in which the bobbin is in engagement with a driving cylinder to a retracted position in which the bobbin is out of engagement with the driving cylinder, and releasable locking means for holding the bobbin in the retracted position which is automatically engaged by movement of the support to the retracted position and which is automatically released by further movement of the support in the same direction in which it is moved to engage the said locking means.

Preferably one of two parts rigid with the supporting structure and the support is provided with a spring biased retaining member and the other with a groove arranged so that on movement of the support to the retracted position the spring biased retaining member enters the groove to retain the support in the retracted position while on further movement in the same direction the spring biased retaining member is disengaged from the groove and an overriding device is moved into its operative position to prevent the retaining member from re-entering the groove. The overriding device may enter the groove so that on the return movement to the engaged position the spring biased member cannot enter the groove and the spring biased retaining member may be carried by the support while the groove may be provided on a part rigid with the supporting structure.

Preferably the part rigid with the supporting structure has a circumferential recess extending around it in which lies and can slide a ring having a gap which in the inoperative position of the device lies opposite the groove, whereas on the said further movement of the support one end of the device enters the groove to prevent the spring biased member from re-entering it on return to the engaged position, the movement of the support relative to the supporting structure being arranged to restore the ring to its inoperative position prior to return of the support to the retracted position. The groove may have the appropriate edge chamfered so as to enable the retaining member to slide out of the groove during the said further movement of the support. Vibration damping

2

mechanism may be provided to suppress vibrations between the bobbin support and the supporting structure.

The invention may be carried into practice in various ways but one example will now be described with reference to the accompanying drawings in which:

FIGURE 1 is in part a cross-section through and in part an elevation of apparatus for supporting a bobbin according to the present invention;

FIGURE 2 is a cross-section on the line 2—2 of FIGURE 1;

FIGURE 3 is a more detailed cross-section of the ring shown in FIGURE 2;

FIGURE 4 is an end elevation of the ring shown in FIGURE 3;

FIGURE 5 is an end elevation of the sliding ring shown in FIGURE 2;

FIGURE 6 is a cross-section through the release pin;

FIGURE 7 is a cross-section on the line 7—7 of FIGURE 6;

FIGURE 8 is a cross-section similar to FIGURE 2 showing the mechanism in the retracted position; and

FIGURE 9 is a similar cross-section to FIGURE 8 showing the mechanism in the position ready to return to the engaged position.

As shown in FIGURE 1 each bobbin support is supported on a shaft 1 forming the supporting structure, the bobbin support comprising a body 2 pivotally mounted on the shaft 1, and having arms 3 extending therefrom supporting between them rotatably at their outer ends a bobbin 4 arranged to engage a driving cylinder 5.

The body 2 has a cylindrical recess 6 in one end housing locking mechanism for retaining the bobbin 4 out of engagement with the driving cylinder 5. The locking mechanism comprises a main locking ring 7, shown more clearly in FIGURE 3, secured to the shaft 1 by means of two grub screws 8, having extending around it a circumferential groove 10 and an axially extending groove 11 in its circumference, with a straight edge 12 and a chamfered edge 13 at its upper side. Arranged to fit in the groove 10 is a sliding ring 14, shown in FIGURE 5, extending through about 300° so as to leave a gap of approximately 60° between its ends 14a and 14b. The dimensions of the ring 14 are such that it fits into the groove 10 with its outer surface flush with the outer surface of the locking ring 7 and such that it is a sliding fit within the groove 10.

Mounted in a bore in the body 2 is a locking pin 15 positioned so that its inner end will engage, when in the appropriate position, the groove 11 and urged radially inwardly by a spring 16. Also positioned in a bore in the body 2 is a release pin 17, shown more clearly in FIGURES 6 and 7 from which it will be seen that it has a flat fish tail like end or tang 18 which fits into the groove 10 between the ends 14a and 14b of the ring 14. The release pin 17 is held in position at its outer end by means of a retaining member 19. The locking assembly is retained within the housing 6 between two rings 20 of fibrous material at either end, which assist vibration damping, by a ring type spring 21 which is kept in place by pressure from a threaded ring 22 engaging the end of the recess 6.

The operation of the assembly is as follows: When the assembly is in the engaged position the bobbin 4 engages the driving cylinder 5 and is retained there by gravity, the disposition of the parts in this position being as shown in FIGURE 2. In this position the body part is free to rotate about the shaft 1 to which the locking ring 7 is secured. When it is desired to disengage the bobbin from the driving cylinder the bobbin support is lifted so that the body 2 rotates about the shaft 1 until the locking pin 15 comes opposite the groove 11 into which it is forced by the spring 16 to hold the body

and hence the bobbin out of engagement with the driving cylinder. During this movement the release pin 17 has pushed the sliding ring 14 around, since it engages its end 14a, and the other end 14b has come directly behind the groove 11, the disposition of the parts in this position being shown more clearly in FIGURE 8. In order to release the body 2 from this locked position it is lifted (i.e. moved once again in the same direction as it is moved towards the locking position) and during this movement the locking pin 15 slides up the chamfer 13 on the groove 11 until it is once again engaging the periphery of the ring 7, and at the same time the release pin 17 pushes the sliding ring 14 round the groove 10 so that it now obstructs the groove 11 and masks off its shape. Thus when the body is released and the bobbin once again moves downwards towards the position in which it will be in engagement with the driving cylinder, the locking pin 15 slides downwards over the sliding ring 14 and passes over the groove 11, back into engagement with the driving cylinder.

What I claim as my invention and desire to secure by Letters Patent is:

1. Apparatus for supporting a bobbin in textile machinery comprising a supporting structure; a bobbin support including supporting means to support a bobbin rotatably thereon, said bobbin support being pivotally connected to said supporting structure about an axis parallel to and displaced from the axis of rotation of said supporting means; a driving cylinder for driving said bobbin by engagement of said bobbin therewith; means for moving said bobbin support about said axis between an engaged position in which said bobbin is in engagement with the driving cylinder and a retracted position in which said bobbin is out of engagement with said driving cylinder, said means comprising a spring biassed retaining member mounted on the bobbin support; a groove in the supporting structure engageable by the spring biassed retaining member in the retracted position to retain said bobbin support in said position; and means for disengaging said bobbin support from the retracted position by further movement of said bobbin support in the same direction as movement towards the retracted position comprising a circumferential recess extending around the supporting structure, a masking member in the form of a ring with a circumferential gap therein mounted in

and slidable with respect to said circumferential recess, said gap being positioned in register with said groove when said bobbin is in the retracted position, means operative by said further movement of said bobbin support to move the gap in the masking member out of register with the groove and to retain said gap in the masking member out of register with the groove after said further movement, said masking member preventing said spring biassed retaining member re-entering the groove on return to the engaged position, and means operative during return movement of the bobbin support relative to the supporting structure after said spring biassed retaining member has passed said groove to restore the masking member to a position with said gap in register with the groove in the supporting structure.

5 2. Apparatus for supporting a bobbin in textile machinery as claimed in claim 1 in which said supporting structure has a cylindrical surface part in which said annular recess is formed, and said masking member has its outer surface flush with said cylindrical surface.

10 3. Apparatus for supporting a bobbin as claimed in claim 1 in which said means to move said gap in the masking member out of register with the groove in said supporting structure during said further movement and said means to restore said gap in register with said groove during said return movement comprises a member in said bobbin support provided with a tang projecting into said gap in the masking member, said tang engaging the ends of the gap in the masking member when said bobbin support is moved.
